UNITED STATES PATENT OFFICE.

BERNARD U. POTTER AND WILLS M. FLEMING, OF HOLYOKE, MASSACHUSETTS,
ASSIGNORS TO WORTHINGTON PUMP AND MACHINERY CORPORATION, OF
NEW YORK, N. Y., A CORPORATION OF VIRGINIA.

PUMP.

Application filed May 18, 1922. Serial No. 561,836.

To all whom it may concern:

Be it known that we, BERNARD U. POTTER and WILLS M. FLEMING, citizens of the United States, residing at Holyoke, county 5 of Hampden, and State of Massachusetts, have invented certain new and useful Improvements in Pumps, fully described and represented in the following specification and the accompanying drawings, forming a 10 part of the same.

This invention relates to improvements in pumps.

It is the especial object of the present invention to provide an improved means for 15 priming pumps, in which a quantity of reserve liquid for the priming operation is held in a reservoir arranged to be filled by liquid from the pump suction air chamber or the suction line delivering to such chamber, 20 and there is provided a valved connection from such reservoir to the pump chamber, whereby such reservoir will be kept filled and its contents be at all times available for delivery directly to the pump chamber independently of the suction valves when priming 25 is necessary.

In the accompanying drawings forming a part of this specification, a horizontal single-acting pump embodying the invention in a 30 preferred form is shown, and this construction will now be described in detail in connection with said drawings and the novel features of the invention then be pointed out in the claims.

35 In the drawings—

Figure 1 is a side elevation, partly in section, showing a single-acting horizontal plunger pump with the priming reservoir connection to the plunger chamber thereof;

40 Figure 2 is a view looking to the left of Fig. 1 and showing the suction air chamber in section, and

Figure 3 is a section on the line 3—3 of Fig. 2.

45 Referring now to the drawings, A indicates generally the pump cylinder casting, B the pump plunger, C, D suction and discharge valves, E the discharge air chamber, F the plunger or pulsation chamber formed by an 50 enlargement of the cylinder space, and G the suction air chamber. The plunger B is reciprocated from the crank shaft through the usual intermediate eccentric and crosshead connections, such, for example, as shown in

United States Letters Patent No. 1406178, 55 granted February 14, 1922, to Fleming and Brigham. While the suction air chamber G may be of any suitable form, it has been shown as approximately circular in cross section (Fig. 3) and may be advantageously 60 located, as shown, contiguous to the plunger chamber F. In the arrangement shown, also liquid from the pump suction line enters chamber G at 11 and passes therefrom at 10 to the pump. 65

In order to assure at all times after the initial operation of the pump, a sufficient quantity of priming liquid which will be available for delivery to the plunger chamber on starting, there is provided, preferably 70 within the suction air chamber G, a priming reservoir 1, which may conveniently be formed integrally with the wall of such chamber, the bottom of such reservoir being above or level with the bottom of the plunger chamber F to facilitate flow of a sufficient quantity of priming liquid from such reservoir to the pump plunger chamber by gravity. The reservoir 1 is also so positioned 75 within the suction air chamber as to be beneath, and therefore directly supplied with liquid from, the suction line inlet 11, whereby the reservoir will always be maintained full of liquid for priming purposes after the pump has once been run. The interior of 80 the reservoir 1 is connected with the plunger chamber F by a pipe 2, in which is interposed a valve 3 of ordinary construction, provided with a hand-wheel 4 for closing or partially closing the same after the pump 85 has been primed and for opening the valve in starting up. If almost closed, so that only a small quantity of water is admitted to the pump at each stroke, the priming is well maintained under long suction lifts or 90 with long suction pipes.

It will be noted that the chamber G is of sufficient height to accommodate the reservoir 1 therein and still have sufficient space thereabove to perform its function as a suction air 100 chamber. The pump, when first operated, may be conveniently primed by filling the reservoir 1 through an orifice 5 in the top of the suction air chamber G, such orifice being thereafter closed by a screw plug 6. 105

The present priming means will be found of especial advantage in those locations where moderate to high suction lifts are en-

- countered, with subsequent frequent loss of priming liquid and failure of the pump to pick up its suction quickly, all of which interferes with the efficiency of the pump.
- 5 The present priming means also will increase the working efficiency of the pump, in that after the pump has caught its suction, liquid flowing into the reservoir will maintain the same full at all times, while the overflow 10 therefrom will pass into the suction connection 10, the pump thus being always ready to be started up quickly, should the air inlet (indicated at 7) for any reason break the vacuum in the suction line, the liquid always 15 in reserve in the reservoir 1 being always available for priming. The valve 3 may be closed after priming, and thus assure a sufficient quantity of priming liquid remaining in the reservoir for future starting. It 20 will be obvious that where the priming means herein shown and described is to be used with a double-acting pump, it will be necessary merely to connect each end of the pump cylinder with the reservoir 1, or with 25 separate reservoirs filled from a single or separate priming chambers, as desired.
- It will be understood that the invention is not to be confined to use with pumps of the particular type shown, but that various 30 modifications and changes may be made in the construction and arrangement of parts shown to meet different requirements, while still retaining the invention defined by the claims.
- 35 What is claimed is:
1. Priming means for pumps, comprising a reservoir having an inlet open to liquid from the pump suction, and means for delivering liquid from said reservoir to the pump chamber independently of the pump 40 valves for priming.
  2. Priming means for pumps, comprising a chamber through which liquid from the suction line passes to the suction valves, a reservoir having an inlet open to the liquid 45 inlet to said chamber, and a connection from said reservoir to the pump chamber for delivering liquid to the latter independently of the pump valves for priming.
  3. Priming means for pumps, comprising a suction air chamber through which liquid from the suction line passes to the suction valves, a reservoir located within said chamber and having an inlet open to the liquid supply to said air chamber, a connection 50 from said reservoir to the pump chamber independent of the suction valves, and a valve for controlling said connection.
  4. Priming means for pumps, comprising a suction air chamber arranged to receive 60 liquid from the pump suction line, a priming reservoir within said chamber and having its inlet open to liquid entering said chamber, a connection from said reservoir to the pump chamber independent of the suction valves, a valve for controlling said connection, and an inlet for filling said reservoir with liquid independently of the suction line.
- In testimony whereof, we have hereunto 70 set our hands.

BERNARD U. POTTER.
WILLIS M. FLEMING.
